UNITED STATES PATENT OFFICE.

ORVILLE D. MORGAN, OF BURKE, WASHINGTON.

CLUTCH.

978,776.

Specification of Letters Patent. Patented Dec. 13, 1910.

Application filed November 27, 1909. Serial No. 530,160.

To all whom it may concern:

Be it known that I, ORVILLE D. MORGAN, a citizen of the United States, residing at Burke, in the county of Grant and State of Washington, have invented new and useful Improvements in Clutches, of which the following is a specification.

This invention relates to automatic safety clutches, the object in view being to provide a device of the character referred to which is particularly designed for use upon the winding drum shaft or donkey engine for general hoisting or other purposes, the mechanism hereinafter described enabling the drum or any reasonable number of drums to be conveniently and safely handled with ease and accuracy and further rendering it possible to use a cable which is partly worn or weakened on a powerful engine without liability of breaking said cable.

One of the main objects of the present invention is to provide positive means for releasing the drum from frictional engagement with the driving gear wheel thereby doing away with the spring now in common use and also doing away with the necessity of renewing and replacing such spring at frequent intervals, an operation which is time-consuming and difficult.

The device also operates as an indicator to the engineer and others as it notifies the engineer when the line or cable is overloaded enabling the trouble to be adjusted and overcome before breaking the line or cable. It also does away with the necessity of a second engineer or assistant.

The invention is not limited to the use of the clutch in connection with any particular make or type of engine or may be used on a variety of engines, such as are used for logging or hoisting purposes or for operating steam shovels and the like and it may also be observed that the clutch, as a whole, will operate equally as well with air, steam or hydraulic power.

With the above and other objects in view, the nature of which will more fully appear as the description proceeds, the invention consists in the novel construction, combination and arrangement of parts as herein fully described, illustrated and claimed.

In the accompanying drawings:—Figure 1 is a vertical longitudinal section through the improved automatic clutch, showing the driving gear wheel, the drum and other parts

in section and showing a drum shaft partly in section and partly in elevation. Fig. 2 is an enlarged sectional view of the operating valve casing and parts associated therewith. Fig. 3 is a sectional view of the same mechanism, taken at right angles to Fig. 2. Fig. 4 is a cross section through the drum shaft taken in line with the key. Fig. 5 is a side elevation of one of the slotted take-up collars. Fig. 6 is an edge view of the complementary take-up collars. Fig. 7 is a plan view of the controller valve. Fig. 8 is an inner face view of the balanced spring seat. Fig. 9 is a side elevation of the clutch-operating piston.

Referring to the drawings, 1 designates the drum shaft upon which the cable holding drum 2 is loosely mounted, said drum embodying the usual heads or flanges 3 and being provided on one side with concentric friction flanges 4 having outwardly diverging friction faces 5.

6 designates the driving gear wheel which is fast on the shaft 1 and which rotates continuously therewith. This gear 6 may be driven in any suitable manner and is provided on the side adjacent to the drum 2 with a friction ring 7 having outer and inner inclined friction faces 8 corresponding in shape with the inclined faces 5 of the friction flanges 4 of the drum 2 so that when the flanges 4 and ring 8 are in frictional contact with each other, the drum is taken up by the gear wheel 6 and revolved, thereby winding the cable or line on the drum.

At one side of the drum and at the corresponding end of the drum shaft 1, there is arranged a cylinder comprising opposite heads 9 and 10, one of said heads 9 being provided with a circumferential flange or rim 11 forming the outer peripheral wall of the cylinder and the other of the two heads being provided with circumferential flanges or lugs 12 adapted to receive bolts 13 for securing the two sections of the cylinder together. Mounted to reciprocate in such cylinder is a hollow piston 14 provided with the usual piston rings 15. Said piston is mounted fast on one end of a piston rod 16, as shown in Fig. 1, the said piston rod passing through a central bore 17 in the drum shaft 1 and being adapted for a limited longitudinal reciprocating movement in said drum shaft when actuated by the move-

ment of the piston 14. At its inner end, the piston rod 16 is provided with a key-way or slot 18 and the drum shaft 1 is provided with a corresponding key-way or slot 19, the said slots 18 and 19 being designed to receive a key 20 as shown in Figs. 1 and 4, whereby the rod 16 and the drum shaft 1 are caused to rotate together. In order to admit of the relative sliding movement between the piston rod 16 and the drum shaft 1, the key-way or slot 19 in the shaft 1 is made of greater length than the slot 18 in the piston rod, as shown in Fig. 1, while extending around the drum shaft 1 is a sectional take-up collar represented in detail in Figs. 5 and 6, in which, it will be observed that said collar comprises a pair of corresponding sections 21 and 22 provided in their inner adjacent faces with slots 23 and 24 which register with each other as shown in Fig. 6, wherein it will be observed that the slots 23 and 24 are of different depths in each of the sections 21 and 22. The object in making the slots 23 and 24 of different depths is to allow for wear in the friction ring 8 so that as said friction ring wears down in use, the drum 2 may be set up closer to the driving gear wheel 6 by removing the key 20 from one set of slots 23 and 24 and inserting the same in another set, as will be readily understood.

By reference to Fig. 1, it will be seen that the key 20 has its ends reduced or made narrower in width as shown at 25, the portions 25 fitting within the slots 23 and 24 while the wider central portion of the key passes through the slots 18 and 19 of the rod 16 and the drum shaft 1. The take-up collar sections 21 and 22 are held in place by means of a sectional retainer housing 26 which, as shown in Fig. 4 is composed of two equal semi-circular sections provided with abutting ears 27 through which are passed fastening bolts 28. By removing the retainer housing 26, the key 20 may be shifted from one of the slots 23 and 24 to another set to compensate for wear in the friction ring, above noted. By the means described the piston rod 16 is connected to the drum 2 so that as the rod 16 is moved endwise by the piston 14 a corresponding movement is imparted to the drum 2 thereby carrying the same toward and away from the friction ring 8 of the driving gear wheel 6.

29 designates the controller valve casing which is arranged on the outer side of the cylinder and provided with a tubular extension 30 which fits in an opening 31 in the adjacent head of the cylinder, as shown in Fig. 1. The outer end of said casing 29 is closed by means of a cap 32 which is removably screwed into the end of the casing, as shown in Fig. 1 and which contains a valve controlling spring 33 the inner end 65 of which bears against a self-balancing

spring seat 34, shown in detail in Fig. 8. Said spring seat is of hollow conical shape in cross section as seen in Fig. 1 and bears against a short pointed projection 35 on the controller valve 36 which controller valve 70 is of hollow cylindrical shape as illustrated in Figs. 1 and 7 and provided with a suitable number of ports 37 which are adapted to move into and out of registry with corresponding ports 38 in a valve tube 39 which extends through the tubular extension 30 of the controller valve casing, as shown in Fig. 1 and has its inner end fitted in a bushing 40 screwed or otherwise fastened in an opening 41 in the adjacent head of the cylinder. 80 The inner end of the valve tube is open so that the steam or other fluid may pass into the cylinder and actuate the piston 14. The controller valve 36 is adapted to slide for a limited distance longitudinally within the 85 valve tube 39 being normally held inward by the spring 33.

42 designates the operating valve casing from which pipes 43 and 44 lead to annular passages 45 and 46 in the controller 90 casing 29, the passages 45 and 46 encircling the valve tube 39, the passage 46 communicating with the interior of the valve tube through the ports 37 and 38 while the passage 43 communicates with an annular space 95 47 around the valve tube and within the extension 30 of the controller valve casing, the annular passage or space 47 opening into an annular groove 48 by which the steam or other fluid enters a passage 49 in 100 the head 10 of the cylinder. The passage 49 registers with a transverse passage 50 in the peripheral wall of the cylinder and this in turn communicates with grooved passages 51 in the piston whereby steam or other 105 fluid is led to the opposite or off side of the piston 14 into the expansion chamber 52.

53 designates the expansion chamber at the opposite side of the piston 14 to which the steam or other fluid is taken from the 110 valve tube 39.

The casing 42 of the operating valve embodies the two passages 54 and 55 which communicate respectively with the pipes 43 and 44 leading to the controller valve and 115 said passages 54 and 55 communicate with a central cylindrical space or chamber 56 in which is mounted the oscillatory operating valve 57 which is adapted to alternately cover and uncover the ports leading to the 120 passages 54 and 55, as clearly illustrated in Figs. 1 and 3. The valve 57 comprises the central cavity 58 which is of sufficient size to bridge one of the passages 54 and 55 and also throw the same into communication 125 with an exhaust chamber 59 which communicates with an exhaust passage 60 to which an exhaust pipe 61 may be connected, as shown in Fig. 2. The operating valve 57 is also provided with a hub portion 62 130

having a square bore adapted to receive the squared portion 63 of the valve stem 64 which extends outward through the valve casing and through a stuffing box 65, the stem 64 being connected fast at its outer end to a hand lever 66 which operates across a segment 67 provided at intervals with notches 68 adapted to be engaged by a spring click pawl 69 having one end attached to the lever 66, the free end thereof being formed to engage successively with the notches 68 in the segment 67.

70 designates a guard segment struck on the same arc as the segment 67 and serving 15 to retain the hand lever 66 in place, said guard segment being provided with terminal extensions or legs 71 which bear against the segment 67 and receive bolts 72 or their equivalent whereby two segments are secured firmly together. The segment 67 is 20 secured to the valve casing by means of bolts or screws 73, as shown in Fig. 2.

From the foregoing description, it will be understood that with the operating valve 57 25 in the reverse of the position shown in Fig. 1, steam or other expansive fluid is admitted through the pipe 43 and annular passage around the valve tube 29 through the passage 49 into the expansion chamber 52 there- 30 by driving the piston 14 away from the gear wheel 6 and acting through the piston rod 16 and key 20 to draw the winding drum 2 out of frictional engagement with the ring 8, thereby leaving the drum 2 free. By 35 moving the valve 57 to the position shown in Fig. 1, the steam or other fluid is allowed to escape through the pipe 43 to the exhaust and at the same time steam is admitted by said valve to the pipe 44, thence it passes 40 through the valve tube 39 into the expansion chamber 53 thereby driving the piston 14 to the left and by means of the piston rod 16 and key 20, drum 2 is forced into frictional 45 engagement with the ring 8 of the gear wheel 6 thus causing said gear wheel to take up the revolving drum 2 for winding the cable or line thereon.

It will thus be seen that I obtain by simple 50 means the positive release between the drum and gear wheel and also an automatic control whereby a weak line is prevented from being broken by being overloaded due to the fact that the friction would admit of the necessary slip to prevent winding the line in 55 case of overloading, the amount of friction being regulated by the adjustment of the tension of the spring 33 which acts on the controller valve 36, the tension being adjusted by screwing the cap 32 inward or outward 60 so as to cause the spring to oppose to a greater or lesser extent longitudinal sliding movement of the controller valve within the valve tube 39. This slipping of the line or cable not only notifies the engineer that the 65 line is overloaded, but also notifies those at-

tending the end of the line to the same effect. It also does away with the necessity of employing a second or assistant engineer.

It will be understood that when the controller valve is in full registry with the ports 70 and in the valve tube, a full flow of steam or other expansive fluid is permitted and this arrangement of parts may be adhered to as long as the line is of full strength. When the line becomes weakened, however, the cap 75 32 is screwed outward so as to relieve the tension of the spring 33 a suitable amount and then the pressure of the steam will operate to force the controller valve 36 outward toward the cap 32 thereby partially 80 closing the ports of the valve and correspondingly reducing the steam pressure entering the cylinder and operating on the piston 14. This produces an appropriate lighter engagement between the drum and 85 the driving gear wheel which will insure slippage between said parts in accordance with the strength of the line or cable wound on the drum. All of the advantages above enumerated are attained by mechanism 90 which is at once simple, reliable and not liable to get out of order. At the same time access may be readily obtained to all of the operative parts of the mechanism for purposes of repair. 95

By reference to Fig. 1, it will be observed that a fluid passage 74 extends from the annular passage 45 to the right beneath the annular passage 46 and communicates with the cavity or space containing the members 100 33, 34 and 35. This passage 74 is intended to carry away to the passage 45 the small amount of accumulation of fluid which is certain to leak between the valve 36 and the valve tube 39. This prevents pressure from 105 forming in the spring containing chamber which would tend to prevent said spring 33 from performing its function. When the controller is working under a light spring 110 tension and a heavy boiler pressure, the ports 37 in the valve 36 will be out of registry with the ports 38 in the valve tube 39, having shifted to the right and reducing the pressure in the chamber 53. When the hand lever 69 is operated or moved to the reversed 115 position from that shown in Fig. 1, the pressure passes through the pipe 43 into the annular passage 45 and thence through the passage 74 as well as the passage 49, 50 and 51. Therefore, the pressure which is admitted through the passage 74 aids the spring 33 to shift the valve 36 to the left, thus bringing the ports 37 and 38 into registry and allowing the exhaust to escape 120 from the expansion chamber 53. 125

I claim:

1. The combination of a driving wheel, a drum adapted to be clutched and unclutched by relative movement of the wheel and drum, a piston for producing such rel- 130

- ative movement, a cylinder in which the piston is mounted, separate passages for admitting fluid to opposite sides of the piston, a valve for admitting fluid to one passage while exhausting fluid through the other, and a valve movable automatically to control the pressure of the fluid acting on the piston in a direction to hold the drum and wheel clutched.
- 10 2. The combination of a driving wheel, a drum adapted to be clutched and unclutched by relative movement of the wheel and drum, a piston for producing such relative movement, a cylinder in which the piston is mounted, separate passages for admitting fluid to opposite sides of the piston, a valve for admitting fluid to one passage while exhausting fluid through the other, a valve movable automatically to control the pressure of the fluid acting on the piston in a direction to hold the drum and wheel clutched, said valve being provided with a port through which fluid passes, one end of the valve being closed to permit pressure 25 of the fluid to act thereon, and an adjustable spring for opposing the movement of the valve under the action of the fluid.
3. The combination of a driving wheel, a drum adapted to be clutched and unclutched by relative movement of the wheel and drum, a piston for producing such relative movement, a cylinder in which the piston is mounted, a tube extending into the cylinder, said tube having ports, a conduit
- leading into the cylinder at the side of the piston opposite to the tube, a sliding valve in the tube having ports adapted to register with the ports in the latter, means for admitting fluid under pressure through the ports in the tube, means for admitting fluid through the conduit alternately with the first-mentioned means, and an adjustable spring pressing on the said valve, said valve being exposed to the pressure of fluid passing into the cylinder through the said tube for causing the valve to vary the effective area of the ports of the tube.
4. The combination with a driving wheel and a winding drum having a relative sliding movement on the same shaft, of coöperating friction elements on said wheel and drum, a cylinder, a fluid operated piston movable back and forth in said cylinder, and connected with the drum shaft for causing a relative movement between said driving wheel and drum to effect an engagement and disengagement of the friction elements thereof, and an automatic pressure controlled valve for regulating the pressure in said cylinder, said valve having combined therewith an adjustable spring tension.
- In testimony whereof I affix my signature in presence of two witnesses.
